UNITED STATES PATENT OFFICE.

HOMER S. ROGERS, OF MILWAUKEE, WISCONSIN, ASSIGNOR, BY MESNE ASSIGNMENTS, TO MILWAUKEE AIR POWER PUMP COMPANY, OF MILWAUKEE, WISCONSIN, A CORPORATION OF WISCONSIN.

PNEUMATIC PUMP.

Application filed February 11, 1920. Serial No. 357,769.

To all whom it may concern:

Be it known that I, HOMER S. ROGERS, a citizen of the United States, residing at Milwaukee, in the county of Milwaukee and State of Wisconsin, have invented certain new and useful Improvements in Pneumatic Pumps, of which the following is a specification, reference being had to the accompanying drawing, forming a part thereof.

This invention relates to pneumatic pumps, and the object of the invention is to improve the construction and operation of pneumatic pumps in the manner to be hereinafter described and claimed.

Referring to the drawing which accompanies this specification and forms a part hereof, which drawing illustrates an embodiment of this invention, the figure of the drawing is a vertical section of a pneumatic pump.

Referring to the drawing, the reference numeral 1 designates a casing partly forming two pump chambers 2 and 3. The pump chambers are provided with water inlet valves 4 and 5 and water outlet pipes 6 and 7 and the water outlet pipes are provided with outwardly opening check valves 8 and 9. The pump chambers are also provided with air inlet ports 10 and 11, air inlet valves 12 and 13, air exhaust ports 14 and 15, and air exhaust valves 16 and 17. The air exhaust ports 14 and 15 are illustrated by the drawing as communicating with a main or common exhaust port 18 with which an exhaust pipe, not shown, can be connected to extend above the surface of the water in an ordinary manner. The air exhaust valves 16 and 17 are interconnected so that one is closed as the other is opened. The drawing illustrates a simple method of interconnecting these valves, their stems 19 and 20 being connected with a lever 21 which is pivoted on a pivot 22, the pivot 22 being supported by the top or cover 23 which closes the top of the casing 1 and completes the pump chambers 2 and 3. The air inlet valves 12 and 13 are carried by pivoted levers 24 and 25 which are provided with weights 26 and 27 heavy enough to close the air inlet valves and keep them closed against the pressure of the compressed air in the air inlet ports. The weights 26 and 27 are connected with the air exhaust valves 16 and 17 so that they will be lifted when the air exhaust valves

are closed, so as to open the air inlet valves 12 and 13. The connection is preferably a loose one such, for example, as that illustrated by the drawings in which pins 28 and 29 engage in slots in lugs 30 and 31 secured to the air exhaust valves. The air exhaust ports 14 and 15 and the air exhaust valves 16 and 17 are made of sufficiently large areas so that the air exhaust valves will be held to their seats, even while supporting the weights 26 and 27, by the difference between the pressures within the pump chambers and outside thereof, so that an air exhaust valve will not be opened until the water level in its pump chamber has receded to a predetermined low water level. The reference numerals 32 and 33 designate motors of sufficient power to force the air exhaust valves 16 and 17 from their seats 34 and 35. The motors 32 and 33 are illustrated by the drawing as of a fluid-pressure type and include flexible diaphragms 36 and 37 of sufficient area to yield the power required. The spaces 38 and 39 between the diaphragms 36 and 37 and the heads 40 and 41 can be placed in communication with the pump chambers 2 and 3 through the pipes 42 and 43, respectively. Valves 44 and 45 establish communication between the pump chambers and the motors 32 and 33, or prevent communication between the pump chambers and the motors, according to the water levels in the pump chambers, these valves being operated by floats 46 and 47.

Compressed air is conveyed to the air inlet ports 10 and 11 from any suitable source of supply by the compressed air pipe 48. A spring 49 is provided as a means for preventing the air exhaust valves from assuming impositive positions while the pump is being transported or installed, for example, but exerts no other function in the pump construction or in the operation of the pump under normal conditions of operation. While this spring is strong enough to lift the weight 26, it is weak enough to be readily compressed by the motor 32 when closing the air exhaust valve 17 and lifting the weight 27.

Bleed holes 50 and 51 are provided for the escape of air from the motors 32 and 33 to prevent their becoming air bound as some air will escape from the water which is utilized as the fluid-pressure medium for trans-

mitting the pressure of the compressed air from a pump chamber to the diaphragm of a motor.

The operation of the pump will be readily understood from an inspection of the drawing. The drawing illustrates the parts in the positions which they occupy immediately after the air exhaust valve 17 has been opened and the air exhaust valve 16 has been closed, with the air inlet valve 13 closed and the air inlet valve 12 open. Water is flowing into the pump chamber 3 and has opened the water inlet valve 5, but the water level has not risen sufficiently high to raise the float 47 and close the valve 45. The compressed air is exerting its pressure upon the water in the pump chamber 2 and is holding the air exhaust valve 16 closed and supporting the weight 26. As the water rises in the pump chamber 3, the float 47 will close the valve 45 and the water inlet valve 5 will close by gravity when the water level in the pump chamber 3 and the exhaust pipe, not shown, has nearly reached the level of the water in which the pump is submerged. If the water in the pump chamber 2 is permitted to escape through the pipe 6, the water level in the pump chamber will be lowered until it is below the line of flotation of the float 46, as the valve 44 is held closed by the difference between the pressures in the pump chamber and outside thereof. When the water level has lowered sufficiently so that the weight of the float 46 overcomes the pressure keeping the valve 44 closed, the valve 44 will be opened suddenly and water will be forced into the motor 32 and force the air exhaust valve 16 from

its seat and close the air exhaust valve 17. When the air exhaust valve 16 is forced from its seat, the weight 26 can drop and close the air inlet valve 12, and when the air exhaust valve 17 is closed the weight 27 will be lifted and the air inlet valve 13 opened. The pump chamber 2 will now fill with water and the water can be forced out of the pump chamber 3 through the pipe 7.

What is claimed is:

1. A pneumatic pump comprising a plurality of pump chambers each provided with a water inlet valve, a water outlet pipe, an air inlet valve, and an air exhaust valve, weights suspended from said exhaust valves, a link connecting the air inlet valve and weight of each chamber, and means connecting the exhaust valves of said chambers to insure a reverse condition of the air valves in said chambers.

2. A pneumatic pump comprising a plurality of pump chambers each provided with a water inlet valve, a water outlet pipe, an air inlet valve, and an air exhaust valve, weights connected to and depending from said exhaust valves, a link connecting the air inlet valve and weight of each chamber, and means connecting the exhaust valves of said chambers to insure a reverse condition of the air valves in said chambers, the connections between said weights and said exhaust valves being such as to permit of slight independent movement of said elements.

In witness whereof I hereto affix my signature.

HOMER S. ROGERS.
